(57) CLAIM

() Term: 14 Years

The ornamental design for enclosure box for large display entry system, as shown and described.

DESCRIPTION

FIG. 1 shows a front view of an embodiment of the present invention; and,

FIG. 2 shows perspective view from the left of an embodiment of the present invention.

The design claimed as the invention does not include the numbering on the buttons, the text “Elite Entry Phone and Logo” in the lower left hand corner and the text on the screen which reads “Welcome to Rancho Vista Estates. To view Directory Use (A↑), (Z↓) keys. To Call a Resident, Dial Their Code. For Further Help, Push (HELP) Key. Elite Entry and Logo”.
